DISPENSING APPARATUS

Joseph De Luca, Brooklyn, N. Y., assignor, by
mesne assignments, to William R. Warner &
Co., Inc., New York, N. Y., a corporation of
Delaware

Application April 21, 1944, Serial No. 532,086

4 Claims. (Cl. 128—272)

1

The present invention relates to apparatus for dispensing and administering solutions. Apparatus which has been used heretofore for the administration of solutions, particularly for the intravenous administration of solutions, has included a device known as a drip meter for visually indicating to the physician or other operator the rate of flow of the solution being injected into the patient in order that the rate of flow could be accurately controlled. Drip meters as used heretofore have existed in the form of separate instrumentalities which were inserted into the tubing extending between the container for the liquid and the injection needle at some convenient point, preferably a short distance below the container. This arrangement has necessitated the use of an apparatus consisting of several parts which has been difficult to keep free from contamination and have required time and care in their assembly in order to insure that the apparatus was in proper working order. It has also been difficult to avoid a high breakage rate on drip meters because they have substantially universally been formed of blown glass. Frequent injury to operators has also resulted through cuts because of breakage of the drip meters.

It is an object of the present invention to provide an apparatus for administering fluids which will be free of all the disadvantages mentioned hereinabove.

It is another object of the present invention to provide an apparatus for administering fluids in which the container for the fluid and the flow-indicating device are embodied in a unitary structure in which one element lends protection to the other.

A further object of the present invention is to provide an apparatus for administering fluids in which a container for the fluid to be administered and the flow-indicating device are packaged and sold as a unit which requires no positioning of the flow-indicating device relative to the container prior to use.

A still further object of the present invention is to provide a simple apparatus having very few parts which can be readily assembled and disassembled, which may be readily cleaned and maintained in a sanitary condition, and which will eliminate any possibility of injury to the operator as well as reduce the possibility of contamination to a minimum.

Other objects and advantages of construction of the apparatus, if not specifically pointed out, will be apparent to those skilled in the art upon recourse to the following detailed description of what is at present considered the preferred embodiment of the invention, taken in connection with the accompany drawing, in which,

Fig. 1 is a fragmentary vertical sectional view of the apparatus,

2

Fig. 2 is another fragmentary vertical sectional view of the apparatus of the invention showing in particular the interior of the flow-indicating device, and

5 Fig. 3 is a horizontal sectional view of the apparatus on a reduced scale taken substantially on the plane indicated by line 3—3 of Fig. 2 and looking in the direction of the arrows.

The present preferred embodiment of the invention 10 comprises a container 10 for the fluid to be administered which may be any desired fluid. The container 10 is conveniently illustrated as being an open-mouthed bottle having a suitable closure 12 in the form of a stopper, preferably formed of rubber or any other desired plastic material, and a supporting band 14 to which a supporting bail 16 is suitably connected to enable the container to be suspended in the inverted position shown from any suitable support during the administration operation.

20 The closure 12 is provided with a vent tube 18 extended through a suitable opening provided in the closure so that when the container is suspended or otherwise placed in the inverted position illustrated in Fig. 1 air can enter through the bottom of the tube and pass within the container 10 to the space above the liquid 20 so as to permit the liquid to freely flow from the container in the manner hereinafter described.

25 The closure 12 is provided with at least one other suitable opening through which the flow-indicating device, indicated generally at 22, is passed and is supported in position, with the lower portion thereof protruding from the container 10 through the closure 12 and the remainder thereof extending into the container, by frictional contact between the exterior of the device 22 and the interior of the opening in the closure plug through which it extends. The flow-indicating 30 device 22 comprises a substantially cylindrically shaped body 24 provided at its upper end, as viewed in Fig. 2, with an opening 26 and provided at its lower end with a nipple 28 to which a suitable tubing 30 is attached in conventional manner. A nozzle 32 is positioned substantially axially within the body 24 of the flow-indicating device and communicates at its lower end with a chamber 34 within the body 24. The body 24 provides a partition between the outlet opening 26 in the nipple 28 and medicinal liquid 20, which partition is provided with a nozzle 32.

35 In the assembly of the dispensing apparatus of the present invention, the closure 12, air vent tube 18 and flow-indicating device 22 are preferably assembled as a unit and inserted in the mouth of the container 10 after the same is filled to any desired level, preferably less than full, with the liquid to be dispensed. During such operation the container 10 is in a position substantially 40 180° reversed from that illustrated in Figs. 1 and

2. Any suitable closure cap (not shown) is then placed over the mouth of the container so as to include the nipple 28 of the flow-indicating device and the apparatus so assembled is suitably sterilized in any desired manner, for example, as by being subjected to a high temperature in an autoclave. The dispensing apparatus is preferably sold in this form and can be packaged, transported and stored without any danger of contaminating the hermetically sealed interior of the dispensing apparatus.

When use is to be made of the dispensing apparatus, the container closure (not shown) is suitably removed and the tubing 30 is passed over the nipple 28 of the flow-indicating device. The opposite end of the tubing 30 is suitably connected to an adapter 38 and any well known type of tubing clamp 36 is preferably positioned on the tubing to control the flow. The clamp is screwed to closed position and the apparatus is inverted as illustrated in Figs. 1 and 2 and is suspended from any suitable hook or hanger at the desired height above the patient who is to receive the fluid to provide the desired hydrostatic head for the administration of the liquid. An injection needle or other suitable injector (not shown) is then placed over the adapter 38 and the clamp 36 is opened slightly which will permit liquid to pass into the opening 26 of the flow-indicating device and escape from the nozzle 32 in the form of separate drops which fall into the chamber 34. The liquid within the chamber 34 then passes into the tubing 30 and thence into the adapter 38 and through the injector so as to expel all air from the tubing and adapter. Contact is then made with the patient, intravenously, subcutaneously or in any other manner desired. By viewing the falling drops in the chamber 34 through the transparent container 10 and the liquid 20 the operator by recourse to a watch or any other desired timing mechanism can conveniently regulate the flow of the liquid into the patient by simple adjustment of the clamp 36.

Upon completion of the administration operation the apparatus is disassembled with a minimum of effort by merely removing the tubing 30 from the nipple 28 and removing the adapter 38 from the opposite end of the tubing. The only apparatus then remaining to be sterilized at the point of use is the injector, the adapter 38 and the tubing 30. The empty container is then either returned to the manufacturer for refilling or it is of sufficiently economical construction to permit of its being destroyed in the event refilling is not convenient.

Since certain changes may be made in the above construction and different embodiments of the invention could be made without departing from the scope thereof, it is intended that all matter contained in the above description or shown in the accompanying drawing shall be interpreted as illustrative and not in a limiting sense.

The invention having been described, what is claimed is:

1. In a dispensing apparatus for administration of fluid to a patient in controlled amounts,

the combination of a flat bottomed bottle, a closure for the bottle, an air vent tube extending from the closure into the bottle, a flow indicating device connected to the closure and extending into the bottle, said device comprising a hollow member and a nozzle having one end projecting into the member and its opposite end terminating without the member, said nozzle being of substantial length relative to its cross-section, whereby liquid from the receptacle flowing from the nozzle at a rate insufficient to provide continuous flow will leave the end of the nozzle projecting into the member in the form of drops.

5 15 20 25 30 35 40 45 50 55 60 65

2. A portable metering type of dispensing apparatus for administration of fluids to a patient comprising a flat bottomed bottle for containing the liquid to be dispensed, a substantially cylindrical element extending into the bottle, means within the bottle providing a drip nozzle for escape of the liquid from the bottle into the cylindrical element in the form of drops, means for admitting air above the liquid in the bottle, and means providing a restricted opening for the escape of the liquid from the cylindrical element.

3. A portable dispensing device for administering liquid to a patient in controlled amounts comprising a transparent receptacle for the liquid to be dispensed, a transparent hollow member disposed within the receptacle and forming a chamber, a nozzle projecting into the hollow member and communicating exteriorly of the hollow member with the said liquid, a closure for the receptacle, and an air vent tube carried by the closure and extending above the liquid in the receptacle.

4. In a dispensing apparatus for administration of fluid to a patient, the combination of a liquid receptacle, a closure for the receptacle, an air vent tube extending from the closure into the receptacle, a flow indicating device connected to the closure and extending away from the closure into the receptacle, said device comprising a hollow member and a nozzle within the receptacle having one end projecting into the member and its opposite end terminating without the member, said nozzle being of substantial length relative to its cross-section, whereby liquid from the receptacle flowing from the nozzle at a rate insufficient to provide continuous flow will leave the end of the nozzle projecting into the member in the form of drops.
